CLAIM

The ornamental design for a putter type golf club head, as shown and described.

DESCRIPTION

FIG. 1 is a rear perspective view of a putter type golf club head showing my new design;
FIG. 2 is a top plan view thereof;
FIG. 3 is a bottom view thereof;
FIG. 4 is an end view thereof;
FIG. 5 is a rear elevational view thereof;
FIG. 6 is an end view taken from the opposite end of FIG. 4; and,
FIG. 7 is a front elevational view thereof.

The broken lines showing a fragmented shaft are for illustrative purposes only and form no part of the design.

FIG. 1

FIG. 2

FIG. 3

FIG. 4

FIG. 5
